PHOTOELECTRIC STOP MECHANISM FOR LOOMS

Robert B. Hutchinson, Yonkers, N. Y., assignor to
 Alexander Smith, Incorporated, Yonkers, N. Y.,
 a corporation of New York

Application September 15, 1950, Serial No. 184,923

10 Claims. (Cl. 139—336)

1

This invention relates to photoelectric stop mechanism for looms and more particularly to mechanism which is responsive to the shuttle motion and is adapted to stop the loom immediately should the shuttle deviate in timing or path from its standard throw.

An object of the invention is to provide a mechanism for stopping the loom in time to prevent injury to the loom or to the shuttle should the shuttle deviate from its normal rate or path of travel.

Another object is to provide, in the case of Axminster looms, mechanism for stopping the loom in response to an overthrow of the needle.

Other objects and advantages will be apparent as the nature of the invention is more fully disclosed.

The invention will be better understood by referring to the following description, taken in connection with the accompanying drawings, in which specific embodiments thereof have been set forth for purposes of illustration.

In the drawings:

Fig. 1 is a transverse section of a loom taken on the line 1—1 of Fig. 2;

Fig. 2 is a longitudinal section taken on the line 2—2 of Fig. 1;

Fig. 3 is a schematic diagram of the photoelectric control circuit;

Fig. 4 is a partial side elevation of an Axminster needle and associated mechanism embodying the present invention; and

Fig. 5 is a schematic diagram showing the photoelectric circuit involved in the system of Fig. 4.

Referring to Figs. 1 and 2, the invention is shown as applied to a loom of standard construction including a reed 10 supported by a lay 11 which extends across the loom and carries the reed, and a reed cap 12 which carries the upper end of the reed and is supported from the lay 11 by brackets 13 of standard construction. The lay 11 is mounted for swinging movement on arms 15 which are journaled to swing about a rod 16. To one or more of the arms 15 is attached a bracket 17 which is connected by a link 18 to a crank pin 19 carried on a crank arm 20 which is attached to a driving shaft 21 and is arranged to reciprocate the arm 15 in response to rotary movement of the driving shaft 21.

The shaft 21 also carries a cam disc 22 having a raised portion 23 engaging a roller 24 which follows the contour of the cam disc 22 and is carried by an arm 25 pivoted to a bracket 26 and carrying a movable contact 27 engaging a stationary contact 28 except when the roller 24 rides over the raised portion 23 of the cam.

2

As shown more in detail in Fig. 2 the lay constitutes a channel member having a top flange 30 on which the shuttle 31 rides and which is adapted to pass under a supporting bed 32 when the lay is in advanced position. The warp 33 extends over the supporting bed 32 and forms a shed 34 through which the shuttle 31 passes.

In the embodiment shown a light bulb 40 is mounted on the reed cap 12 directly over the path of the shuttle 31 and midway of its throw. A photoelectric cell 41 is mounted in the upper flange 30 of the lay directly beneath the light 40 so as normally to receive the rays of the light 40. The cell 41 is mounted flush with the upper surface of the flange 30 so that it does not interfere with the normal throw of the shuttle. A brush 43 is mounted on the lower surface of the supporting bed 32 in a position to sweep over the cell 41 as the lay is returned to its advanced position, so as to remove any lint or dirt from the top surface of the lay which would interfere with the passage of light from the bulb 40 to the cell 41.

In the circuit shown in Fig. 3 the photoelectric cell 41 is connected to the grid 45 of an amplifier tube 46 and through a battery 47 to the cathode 48 of the tube 46. The tube is provided with an anode 49 which is connected through a coil 50 of a relay 51 and battery 52 to the cathode 48. A motor 55 which constitutes the driving motor of the loom is connected to a three phase line 56 through a circuit breaker 57 which is controlled by a solenoid 58. A D. C. line 59 is connected through contacts to be closed by arms 60 of the circuit breaker 57 to two sides of the three phase line 56 on the motor side of the circuit breaker. The circuit breaker is so designed that when the solenoid 58 is deenergized the contacts of the three phase line 56 are open and the contacts of the D. C. line 59 are closed, and when the solenoid 58 is energized, the contacts of the D. C. line 59 are opened and the contacts of the three phase line 56 are closed.

One side of the solenoid 58 is connected through a battery 62 and a line 63 to a contact 64 to be engaged by an armature 65 of the relay 51 when the latter is deenergized. The armature 65 is connected by a line 66 to the other side of the solenoid 58. The cam actuated contact 27 is connected to the line 63 and the stationary contact 28 is connected to the line 66.

In the operation of this device the photoelectric cell 41 is so connected to the amplifier tube 46 that the coil 50 of relay 51 is energized when the light from the source 40 reaches the photocell 41, but is deenergized during the brief period while the light rays are cut off due to the passage of

the shuttle 31 over the photocell 41. Hence the contact 64 is normally held open, but is closed during the brief periods while the shuttle is over the photoelectric cell 41.

The cam 22 which is driven by the main drive shaft 21 makes a complete revolution for each shuttle throw. Hence the cam may be synchronized with the normal movement of the shuttle over the lay 11 and is so disposed on the shaft 21 that the raised portion 23 of the cam actuates the arm 25 so as to open the normally closed contact 27 at the instant that the shuttle in its normal movement would be over the photoelectric cell 41.

In the normal operation of the loom the solenoid 58 is maintained energized by the normally closed contact 27 except during the periods when the shuttle should be passing over the cell 41 if it is operating normally. The contact 64 is normally open due to the action of the light rays on the cell 41, but is allowed to close during the periods of actual shuttle passage over the cell 41. Hence if the shuttle passes over the cell 41 at the predetermined times the solenoid 58 will be maintained energized, and the loom will continue in operation. However, if during the period that the contacts 27 and 28 are opened by the cam 22, the shuttle is not in a position to intercept the light rays to the cell 41, both contacts 64 and 27 will be open at the same time and the solenoid 58 will be de-energized, allowing the circuit breaker 57 to shift its position to open the three phase line 56 and close the D. C. line 59. The opening of the three phase line 56 removes the energizing force of the motor 55 and the closing of the D. C. line 59 places a D. C. voltage across one phase of the line 56 and serves to stop the motor 55 immediately without allowing the motor to drift to a stop due to the inertia of the parts. The result is to stop the loom instantly so that the stroke of the lay is not completed. It is then possible to remedy the defect which has produced the displacement in time of the shuttle before the weaving proceeds, thereby preventing damage to the shuttle or to the parts of the loom which might otherwise occur if the lay were allowed to complete its stroke.

While the photocell 41 has been shown as placed at the center of the shuttle path for purposes of illustration, it is to be understood that a plurality of such light cells may be used located at different points on the lay, each of which are connected in circuits similar to that of Fig. 3 and timed with the normal shuttle movement so that a displacement of the shuttle at any point of its travel from its normal rate of movement would stop the loom instantly.

The same system may be applied to an Axminster loom as indicated in Figs. 4 and 5, in which the Axminster needle 70 is reciprocated in the usual manner over a track 71. In the embodiment shown a shield 72 extends upwardly from the needle carriage 73 which rides on the track 71 and a pair of light cells 75 and 76 are disposed in the path of the shield 72. In the embodiment shown the light cell 75 is assumed to be located at the center of travel of the needle and the light cell 76 is located just beyond the normal path of travel of the needle so that the light cell 76 is cut off by the shield 72 only in the event of an overthrow of the needle. The needle is driven as in standard Axminster loom practice, the details of which are not included herein. In the circuit diagram of Fig. 5 a driving motor 80 constitutes the driving motor for the needle carriage 75

73. This driving motor is supplied with three phase current from an A. C. line 81 controlled by a circuit breaker 82 and is adapted to be supplied with direct current from a line 83 which is also controlled by the circuit breaker 82, the control being similar to that shown in Fig. 3. The circuit breaker 82 is actuated by a solenoid 85 one side of which is connected through an armature 86, contact 87, line 88 to armature 89 of a relay 90 and to the cam actuated arm 91. The other side of the solenoid 85 is connected by a lead 92 through battery 93, and lead 94 to stationary contact 95 engaging contact 98 on the cam actuated arm 91, and by a lead 96 to the contact 97 of the relay 90. The arm 91 is actuated by a cam 99 similar to the cam 22 above mentioned and driven from the main drive shaft 100 which is actuated by the motor 80. The relay 90 is provided with a coil 102 which is connected in series with a battery 103 between the cathode 104 and anode 105 of tube 106. The grid 107 of the tube 106 is connected through photoelectric cell 75a and battery 108 to the cathode 104.

The relay armature 86 is actuated by a relay coil 110 which is connected through a battery 111 between the cathode 112 and anode 113 of amplifier tube 114 having a grid 115 connected through a photoelectric cell 76a and a battery 116 to the cathode 112. The photoelectric cells 75a and 76a are disposed to receive light from the sources 75 and 76 respectively except when the light is intercepted by the shield 72.

In the operation of this system the motor 80 continues to operate while the solenoid 85 is energized. The solenoid 85 is maintained energized by the normally closed cam actuated contact 98 except when the cam 99 is in the position corresponding to the center position of the needle 70. When the needle is in this position however the light cell 75a is deenergized by the shield 72 passing through the light beam from the source 75 and deenergizes the winding 102 thereby releasing the relay 90 and closing the contact 97. Hence the loom continues to operate as long as the needle is properly timed to cut off the light to the cell 75a at the instant that the contact 98 is opened by the cam 99. However, in the event that the needle is improperly timed, the contacts 97 and 98 are both open at the same time and the solenoid 85 is deenergized and immediately stops the motor 80 as in the previous embodiment.

In addition to the above, the contact 87 is normally held closed by energization of the photoelectric cell 76a. If however the needle should over-throw beyond its normal stroke, the light from the cell 76 would be cut off by the shield 72, thereby deenergizing the photoelectric cell 76a, deenergizing the relay coil 110 and opening the contact 87, thereby deenergizing the solenoid 85 and immediately stopping the loom in the manner above described.

It is to be understood that in this embodiment also a single photoelectric cell 75a has been shown at the center of the needle path. However a plurality of such cells may be disposed along the path and provided with properly timed cams to stop the loom immediately in the event of any deviation of the needle from its proper timing.

Although specific embodiments have been shown for purposes of illustration it is to be understood that various changes and adaptations may be made therein as will be readily apparent to a person skilled in the art.

What is claimed is:

1. In a loom having a driving motor and a yarn carrier actuated thereby in a normal timed sequence, an energizing circuit for said driving motor, switch means normally connecting said energizing circuit to drive said motor, trip means to cause said switch means to disconnect said energizing circuit from said motor, a second switch means, means driven by said motor and synchronized with the normal carrier travel to actuate said second switch means at a predetermined time in said travel, a third switch means, a photoelectric cell disposed at a point in the path of said carrier corresponding to said predetermined time, a circuit connecting said photoelectric cell to actuate said third switch means when the light on said cell is intercepted by said carrier, and a circuit connecting said second and third switch means to actuate said trip means to stop said motor whenever said second and third switch means are not operated in proper timed relationship.

2. In a loom having a driving motor and a yarn carrier actuated thereby in a normal timed sequence, an energizing circuit for said driving motor, switch means normally connecting said energizing circuit to drive said motor, trip means to cause said switch means to disconnect said energizing circuit from said motor, a second switch means having normally closed contacts, means driven by said motor and synchronized with the normal carrier travel to open said contacts momentarily at a predetermined time in said travel, a third switch means having normally open contacts, a photoelectric cell disposed at a point in the path of said carrier corresponding to said predetermined time, a circuit connecting said photoelectric cell to close said last contacts momentarily when the light on said cell is intercepted by said carrier, and a circuit connecting said second and third switch means to actuate said trip means to stop said motor whenever said contacts are open simultaneously.

3. In a loom having a driving motor and a yarn carrier actuated thereby in a normal timed sequence, an energizing circuit and a brake circuit for said driving motor, switch means normally connecting said energizing circuit to drive said motor, trip means to cause said switch means to disconnect said energizing circuit and connect said brake circuit to said motor, a second switch means, means driven by said motor and synchronized with the normal carrier travel to actuate said second switch means at a predetermined time in said travel, a third switch means, a photoelectric cell disposed at a point in the path of said carrier corresponding to said predetermined time, a circuit connecting said photoelectric cell to actuate said third switch means when the light on said cell is intercepted by said carrier, and a circuit connecting said second and third switch means to actuate said trip means to stop said motor whenever said second and third switch means are not operated in proper timed relationship.

4. In a loom having a driving motor and a reed and yarn carrier actuated thereby in a normal timed sequence, a driving circuit and a brake circuit for said driving motor, switch means normally connecting said driving circuit to drive said motor, trip means to cause said switch means to disconnect said driving circuit and to connect said brake circuit to said motor, a switch, cam means driven by said motor and synchronized with the normal carrier travel to actuate

said switch at a predetermined time in said travel, a photoelectric cell disposed at a point in the path of said carrier corresponding to said predetermined time, a second switch, a circuit connecting said photoelectric cell to actuate said second switch when the light on said cell is intercepted by said carrier, and a circuit connecting said first and second switches to actuate said trip means to stop said motor whenever both switches are not actuated in proper timed relationship.

5. In a loom having a lay carrying a reed and a shuttle disposed to pass along said lay, a driving motor actuating said reed and shuttle in a normal timed sequence, an energizing circuit for said driving motor, switch means normally connecting said energizing circuit to drive said motor, trip means to cause said switch means to disconnect said energizing circuit from said motor, a second switch means, means driven by said motor and synchronized with the normal shuttle travel to actuate said second switch means at a predetermined time in said travel, a photoelectric cell disposed at a point along said lay corresponding to said predetermined time, a third switch means, a circuit connecting said photoelectric cell to actuate said third switch means when the light on said cell is intercepted by said shuttle, and a circuit connecting said second and third switch means to actuate said trip means to stop said motor whenever said last switch means is not actuated in proper timed relationship.

6. In a loom having a lay carrying a reed and a shuttle disposed to pass along said lay, a driving motor actuating said reed and shuttle in a normal timed sequence, an energizing circuit and a brake circuit for said driving motor, switch means normally connecting said energizing circuit to drive said motor, trip means to cause said switch means to disconnect said energizing circuit and to connect said brake circuit to said motor, a second switch means, means driven by said motor and synchronized with the normal shuttle travel to actuate said second switch means at a predetermined time in said travel, a photoelectric cell disposed at a point along said lay corresponding to said predetermined time, a third switch means, a circuit connecting said photoelectric cell to actuate said third switch means when the light on said cell is intercepted by said shuttle, and a circuit connecting said second and third switch means to actuate said trip means to stop said motor whenever said second and third switch means are not actuated in proper timed relationship.

7. In a loom having a lay carrying a reed and a shuttle disposed to pass along said lay, a driving motor actuating said reed and shuttle in a normal timed sequence, an energizing circuit and a brake circuit for said driving motor, switch means normally connecting said energizing circuit to drive said motor, trip means to cause said switch means to disconnect said energizing circuit and to connect said brake circuit to said motor, a second switch means having normally closed contacts, cam means driven by said motor and synchronized with the normal shuttle travel to open said contacts momentarily at a predetermined time in said travel, a photoelectric cell disposed at a point along said lay corresponding to said predetermined time, a third switch means having normally open contacts, a circuit connecting said photoelectric cell to close said last contacts momentarily when the light on said cell

is intercepted by said shuttle, and a circuit connecting said second and third switch means to actuate said trip means to stop said motor whenever said contacts are open simultaneously.

8. In an Axminster loom having a reed and a needle carrier, a driving motor actuating said reed and needle carrier in a normal timed sequence, an energizing circuit and a brake circuit for said driving motor, switch means normally connecting said energizing circuit to drive said motor, trip means to cause said switch means to disconnect said energizing circuit and to connect said brake circuit to said motor, a second switch means, cam means driven by said motor and synchronized with the normal needle carrier travel to actuate said second switch means at a predetermined time in said travel, a photoelectric cell disposed at a point in the path of said carrier corresponding to said predetermined time, a third switch means, a circuit connecting said photoelectric cell to actuate said third switch means when the light on said cell is intercepted by said needle carrier, and a circuit connecting said second and third switch means to actuate said trip means to stop said motor whenever said second and third switch means

are not actuated in proper timed relationship.

9. In an Axminster loom as claimed in claim 8 a second photoelectric cell disposed at a point beyond the normal needle path such that the light thereon is intercepted when the needle is in overthrow position and a circuit connecting said last photoelectric cell to actuate said trip means to stop said motor when the light on said second photoelectric cell is so intercepted.

10. In a loom having a lay and a bed under which the lay passes at the forward end of its stroke, a photoelectric cell disposed in the top surface of said lay and a brush attached to said bed in a position to sweep over said cell as the lay passes thereunder.
